IGNITER FOR INTERNAL-COMBUSTION ENGINES.

1,268,322.

Specification of Letters Patent. Patented June 4, 1918.

Application filed February 9, 1914, Serial No. 817,585. Renewed August 10, 1917. Serial No. 185,633.

To all whom it may concern:

Be it known that I, WILLETT F. CLARK, a citizen of the United States, and a resident of Phoenix, in the county of Maricopa and State of Arizona, have invented certain new and useful Improvements in Igniters for Internal-Combustion Engines, of which the following is a specification.

My invention relates to devices for igniting inflammable substances, such as the gases utilized in the operation of internal combustion engines; and the primary object thereof is to provide an igniter having a suitable valve-controlled passage leading to the inside of the engine to admit a cleaning medium or a motive agent in the shape of a priming material or part of a fuel charge.

A further and quite important object of my invention is to provide an igniter in which the passage above mentioned is arranged to enable the valve therein to be closed by gravity as well as by the compression of the fuel; whereby the closing of valve, except when the valve is required to be open, will be insured.

Another object of my invention is to provide an igniter of the electrical type in which at least one electrode can easily be adjusted; and at the same time suitably packed against leakage; in order to regulate the spark and clean the spark points when necessary.

My invention is fully illustrated on the accompanying drawings, the same characters of reference being employed to indicate the same parts on all the views. On said drawings

Figure 1 is a longitudinal section of one form of my igniter;

Fig. 2 is an end elevation of the parts shown in Fig. 1; certain elements being omitted;

Fig. 3 is a section of a band inclosing a passage having a valve and adapted to conduct to an opening or passage leading to the inside of the igniter;

Fig. 4 is a section of a modified form of band inclosing such a passage;

Figs. 5 and 6 are sectional views of details; and

Fig. 7 is a longitudinal section of a modification of my igniter with the band inclosing a passage omitted.

My igniter or spark plug is of the jump

spark or high tension variety and it comprises the usual supporting shell or casing 1 having an external collar 2 and screw-threaded inner end to enable it to be mounted on an internal combustion engine. The casing is of course hollow, having a longitudinal bore extending through it, this bore 60 having an internal shoulder 4. The end of the bore opposite the threads 3 has internal screw-threads 5, and the casing receives an insulator sleeve 6 having a collar 7. This collar 7 fits the bore beyond the shoulder 4 and a nut or gland 8 engages the threads 5 and one end of the collar to secure the insulator in the casing 1. These elements are well known and form no part of my invention.

The inner portion of the bore in the casing 1 receives a tubular or thimble-shaped electrode 9 having a flange 10 to engage the shoulder 4. Normally the collar 7 on the insulator is forced by the nut or gland 8 against the flange 10 to hold it against the shoulder 4 and secure these parts in tight position. The inner end of the electrode 9 is contracted and terminates in an opening 11, at the inner end of the shell 1.

A central longitudinal bore is also provided in the insulator 6; and this bore receives an electrode stem 12, slidably and rotatably mounted therein and branched at its inner end to provide a plurality of spark points 13. The outer end of the insulator 6 has a collar 14 which engages a flange or shoulder on the sleeve and is received by a cap 15 through which the stem 12 passes. Between the cap and the end of the sleeve is a washer 16, and the collar 14 may be extended slightly beyond the end of the sleeve to receive this washer, or it may terminate flush with the sleeve, so that the washer can be placed over the end of the sleeve and the collar 14 also. At its outer end the passage through the sleeve 6 is counterbored as indicated at 6', and this counterbored end provides a space for packing shown at 12'. The function of the washer is to hold the packing in place and the stem 12 100 can slide through both the washer and the packing.

The passage through the cap 15 receiving the stem is also counterbored at the end adjacent to the washer when the cap is in place, 105 and this counterbored end enables the cap to

be slipped on the stem 12 very readily. It may be filled with packing also if desired.

The stem is threaded, and the threads extend along the stem 12 from the outer end 5 almost to the washer 14, when the plug is assembled. The cap 15 is threaded to engage the stem 12 so that the position of the stem may be regulated. On the stem 12 beyond the cap is a nut 17, threaded thereon, and 10 the stem terminates in a flattened or wedge-shaped end 18. This end can be engaged to enable the stem 12 to be turned by a cap 18' having a bore extending into the same from one end and having a flange at the other end 15 to enable it to be embedded in an insulator disk 18^a. This disk eliminates the danger of the operator getting a shock when the stem 12 is adjusted. The bore in the cap 18' has its inner end shaped to engage the flat 20 end 18 of the stem snugly, so that when the cap 18' is placed on the stem it can be turned by hand to rotate the stem.

The nut 17 is to hold a conductor between the same and the cap 15, and it further 25 serves to lock the stem 12 in position. Cap 15 fits tightly on the end of the sleeve around the flange 14, and the disk 18^a and cap 18' may remain permanently on the stem 12. To clean the gap, or to adjust the length 30 thereof, the disk 18^a is held by hand, and the nut 17 loosened. The disk 18^a is then turned to rotate the stem till the points 13 touch the thimble 9. This breaks up any soot or oil and clears the spark points so that they 35 can be used further. The disk 18^a is then turned the other way so as to separate the spark points 13 from the thimble, thus reestablishing the gap. By making the threads on the stem 12 of convenient pitch, 40 as sixteen to the inch, the amount of separation of the points 13 from the thimble 9 can be determined for each rotation of the disk. As different types of engines require 45 different spark gaps, this method of determining the spark gap is very important and enables the operator to meet the requirements of engines of various makes, even while running; that is, he does not have to stop the engine to adjust the gap at all.

50 The washer 16 prevents the packing 12' from getting into the threads on the stem 12.

The elements thus far described are common to all forms of my invention; but in 55 the form illustrated in Figs. 1, 2 and 3 I provide the casing 1 with an external circumferential groove 19 having four elongated openings 19' leading into the casing 1. The groove is between the collar 2 and the shoulder 4, and this section of the casing 1 is preferably conical. Around this 60 section fits snugly a band 20 inclosing a passage 21 having a port 22 leading to groove 19. The one end 23 is adapted to make joint with a conduit leading thereto; and 65 the other end is closed by a nut 24. The

port 22 is between the nut 24 and a seat 25 in the passage 21, and this passage is controlled by a ball-valve 26 which engages the seat 25, this seat being located beyond the valve 26 passing from the port 22 toward 70 the end 23. When the igniter is in horizontal position, as in the side of a gas engine, the band 20 will be so placed that the end 23 of the passage 21 will be uppermost, and the seat 25 lowermost. The passage 21 75 will extend down to the seat and then up to the port 22. Hence, except when the valve is forced open to allow substances to pass into the igniter, the valve 26 can be moved by gravity to close the passage. Obviously 80 another valve having a different shape may be employed if desired. The casing 1 is exteriorly screw-threaded at 27 to receive a nut 28 to hold the band in place. The tube 9 has four holes 19'' to register with the 85 holes 19'.

I make use of my igniter shown in Figs. 1, 2 and 3 by securing it to the side of an engine, so that it will be horizontal, as above stated. The port 22 will register with 90 groove 19, and I provide four openings 19' and 19'', so that they will all register more or less in any position of casing 1 and thimble 9. When the plug is on the engine, the passage 21 must extend upward, and seat 25 95 be lowermost. The end 23 is connected to the carburetor, manifold pipe, or other source of fuel supply, and some fuel is led into the gas engine by way of the igniter. The passage can also receive a priming 100 agent, or an agent such as kerosene to clean the electrodes; and for this purpose suitable connections are provided. Such connections are not here shown or described; but are fully set forth in my copending application for a patent on a spark plug system 105 with which my igniter is adapted to be used.

For an igniter which is to be vertically mounted when in use, as in the head of a 110 gas engine cylinder, I employ a modified form of ring shown at 20' on Fig. 4. This ring is a conical frustum having its larger end as the lower end; and it has a passage formed within a radial boss or projection 115 29, which extends outward from the axis of the igniter. This boss has a passage corresponding to the passage 21 and having a sloping bottom 30 leading from the port 22 to the seat 25. In this form the valve is 120 also free to close by gravity; and the outer end of the boss is connected to a carburetor or manifold the same as the passage 21. A stop 31 may be placed between valve 26 and the opening 22.

In case I desire or find it necessary to dispense with the band 20 or 20', and the feeding of the fuel or cleaning agent to the igniter, I utilize the form of my invention illustrated in Fig. 7. This modification is 130

very efficient and so constructed as to allow of ready adjustment of the electrodes 9 and 13. Although not shown on Fig. 7, the cap 18' and disk 18" will of course be used with this form of igniter.

I desire to state that I have obtained excellent results in practice with the various forms of igniters herein set forth. The use of the forms allowing the admission of part 10 of the fuel or the cleaning agent enables me to secure a rich fuel mixture adjacent the spark points inside the engine; and thus the liability of a misfire is greatly lessened and may be practically obviated. At the same 15 time I can make the starting easier by priming the engine through the igniter; or, should the spark points ever become fouled, they can be easily cleaned by running kerosene into the casing 1. As soon as the substance 20 to be forced into the casing 1 has passed the valve 26 the latter can be actuated by gravity to engage its seat 25, and the passage is therefore closed at once. Any likelihood of leakage when the compression 25 stroke of the piston begins is entirely eliminated. By providing four elongated holes 19' in the casing 1 and four similarly placed holes 19" in the thimble 9 I insure having these holes in registry more or less for any 30 relative position of the casing and thimble as above stated. This result I obtain by making each of the openings in the casing and thimble a little over one-eighth of the circumference. The motive agent or cleaning 35 agent thus enters the igniter at four different points and the operation is so much more efficient for that reason. The passage in the band, the groove 19 and the openings 19' and 19" of course constitute a continuous 40 passage.

It is to be understood of course that only part of the fuel charge of the engine passes through the passage 21, the main portion of the charge passing through the inlet valves 45 in the usual way. The passage of part of the charge through the igniter makes it self-cleaning under ordinary circumstances; and if the spark points should ever become fouled, a little kerosene will suffice to clear 50 them of any foreign substances. Kerosene may also be admitted to the cylinder through the igniter to clean the valves, piston rings, and other parts.

It will be understood that the nut 28 may 55 have any desired polygonal shape. I prefer to make it octagonal, though it is shown as a hexagon. The same may be said of the other polygonal parts of my igniter.

The plug shown in Fig. 7 may have a 60 polygonal section 32 adjacent the collar 2 to afford a wrench hold. In the other form the collar 2 may serve this purpose. The plug of Fig. 7 is simpler and cheaper to make than the first form of my plug, and 65 can be readily cleaned and adjusted; but the

first form of my plug has the advantage of being self cleaning and the other advantages above noted.

The nut on the stem 12 serves not only to bind the conductor in place, so that any kind 70 of conductor may be used but it also serves to hold the stem in adjusted position. This nut when screwed up will secure the stem with its inner branched end drawn back as far as may be required in the bore in the 75 sleeve 6, but with the points 13 protruding to within easy sparking distance of the thimble or bushing 9. The stem can be moved to scrape off the points 13, and turned as above stated to move the points 13 opposite fresh sparking surfaces in the thimble 9.

I wish to call attention to the fact that the thimble 9 is held in the casing 1 by the collar on the sleeve 6, and the same nut 8 secures both the thimble and the sleeve in 85 place. To remove the thimble the sleeve is taken out first, and then the thimble 9 can be readily removed also. This thimble is easy and cheap to make, and only the thimble and the porcelain need to be replaced to make an entirely new plug. The stem 12 slides easily through the sleeve and washer 16 and packing 12' and is inserted from the inner end of the sleeve 6. Should the porcelain sleeve ever crack or be otherwise damaged it can be removed and thrown away, but the stem and the other parts associated with it applied to another porcelain sleeve to make the plug ready for further use.

Having described my invention, what I claim as new and desire to secure and protect by Letters Patent of the United States is:—

1. An igniter comprising an insulator 10 having a bore, an adjustably mounted conductor in said bore, and a cap receiving one end of the insulator, the adjacent end of the bore being enlarged to receive packing to be compressed against the inside of the cap.

2. An igniter comprising a casing having an opening or passage to admit a cleaning or a motive agent, a band surrounding the casing and inclosing a passage communicating at its inner end with the opening, and a valve in the passage in the band, the said passage extending downward adjacent the opening when the igniter is mounted, and having a seat beyond the valve, whereby the valve can be actuated by gravity to close the passage.

3. An igniter comprising a casing having a plurality of openings leading therethrough from the outside to the inside thereof, a groove on the outside of the casing communicating with said openings and means engaging the casing and covering the groove, and having an opening or passage leading to the groove.

4. An igniter comprising a casing and a

tubular electrode inside the casing, the casing and the electrode each having a plurality of openings therethrough, said openings being of such angular extent that the openings in the electrode will register with the openings in the casing for any relative position of the electrode and casing.

5. An igniter comprising a casing and a tubular electrode inside the casing, the casing and the electrode each having a plurality of openings leading to the inside of the same and located at different points around the electrode and casing, said openings being of such angular extent that the openings of the electrode will register with the openings in the casing for any relative position of the casing and the electrode.

6. In an igniter, a casing and a removable tubular electrode therein having a contracted opening at one end and an external flange at the other end, and being provided with a plurality of openings located at different points around the same, between the flange and the opening.

20 7. An igniter comprising a casing having an insulator sleeve therein, said sleeve having a longitudinal bore, an electrode stem adjustably received in said bore, said stem extending beyond the outer end of the sleeve and having its outer end threaded, the outer end of the bore being enlarged, packing in said enlarged end, a washer covering the packing to hold said packing in said end and prevent the same from engaging the thread-

ed end of the stem, and a cap, having a bore 35 to receive the stem receiving the outer end of the sleeve to secure the washer in place.

8. An igniter comprising a casing having a pair of spark terminals and an exterior conical section provided with a groove there- 40 in, the casing having openings connecting the groove with the inside of the casing, a band having an interior conical surface encircling said section, said band having a passage leading to said groove, and means 45 engaging said band and said casing to force said band to fit tightly upon said casing.

9. An igniter comprising a casing having an insulator sleeve therein, said sleeve having a longitudinal bore, an electrode stem 50 received in the bore, said stem being arranged to project from the sleeve at its inner end to provide a spark terminal, the outer portion of the stem also protruding from the sleeve, said outer portion being 55 threaded and terminating in a flattened extremity, an internally threaded cap on the outer end of the sleeve engaging the threaded portion, and an insulator cap to receive the said extremity, whereby the stem can be 60 adjusted in the sleeve.

Signed at Louisville, in the county of Jefferson and State of Kentucky.

WILLETT F. CLARK.
